UNITED STATES PATENT OFFICE

2,296,926

WINDING MACHINE

Harold Wood Hitchcock, Apponaug, R. I., assignor
to Universal Winding Company, Boston, Mass.,
a corporation of Massachusetts

Application November 28, 1941, Serial No. 420,880

19 Claims. (Cl. 242—39)

The present invention relates to winding machines and particularly to an improved sizing device for arresting the winding operation when the package being wound reaches a predetermined size.

In the present specification and claims the term "package" is used in a general sense to indicate any form of wound mass and the term "yarn" is intended to apply to all kinds of strand material whether textile or otherwise.

One object of the invention is to provide an improved sizing device for controlling the stopping mechanism of the machine to cause it to act promptly with precision and accuracy to arrest the winding when the package reaches the predetermined size for which the device is set.

Another object is to provide a device of the type indicated adapted to be positively-actuated by power-operated means without causing undue pressure on the package being wound.

Another object is to provide a device of the type indicated in which the power-operated means are actuated by the separation between the winding spindle and the thread-guide which distributes the yarn on the package.

Another object is to provide a device of the type indicated with micrometer adjusting means for setting it to accurately control the size of the package being wound.

Another object is to provide a device of the type indicated which can be applied to winding machines already in use without material alteration in the structure or arrangement thereof.

Further objects of the improvement are set forth in the following specification which describes one preferred embodiment of the invention, by way of example, as illustrated by the accompanying drawings. In the drawings:

Fig. 1 is an end-elevation of a winding machine of conventional type showing the present invention applied thereto and illustrating the parts of the machine in position at the start of a winding operation;

Fig. 2 is an enlarged end-elevational view of the machine with certain of the parts shown in section and illustrated in position at the completion of a winding operation;

Fig. 3 is an enlarged part-sectional side elevation of the fore part of the winding machine; and

Fig. 4 is a perspective view of the reciprocable knock-off element or pitman which is adapted to release the detents which maintain the driving mechanism of the machine operative.

In the present specification and drawings the

invention is described and illustrated as applied to a usual type of winding machine having a positively-driven spindle on which the package is wound and a reciprocating thread-guide for traversing the strand longitudinally of the spindle. It is to be noted, however, that the present improved sizing device is adaptable for use with other types of winding machines and consequently the invention is not limited as to its mode of application. In winding machines of the present type it is common to provide means for arresting the winding operation when the package reaches a predetermined size, and such stopping means are usually actuated by the separation of the winding spindle and thread-guide as caused by the increase in diameter of the winding package. The thread-guide is usually mounted on a pivoted frame which is counter-weighted to maintain the guide in close contact with the package during the winding and in previously-used sizing devices wedges or like means are engaged by the guide-supporting frame as the package reaches the desired size to cause the wedging action to release detent-means which normally hold the stopping mechanism inoperative.

Under present day practice it is desirable for many purposes, for example in winding soft cops for dyeing, in handling delicate lofty materials, and in other instances, to avoid undue pressure of the guide on the surface of the package during winding, particularly as the package approaches its full size. In other words, it is essential that the thread-guide shall bear against the package with only light pressure and it has been found that with the usual sizing device the force required to actuate the wedging or similar device to release the detents for the stopping mechanism causes considerable pressure to be exerted on the guide and by the guide against the package. As a result the yarn being wound is liable to be crushed and flattened and the package itself distorted in shape, thereby causing its ends to bulge and the coils of yarn to be displaced which prevents free delivery of the material in unwinding it.

To overcome this difficulty and the disadvantages of previously-used sizing devices the present invention provides power-operated means actuated from the driving mechanism of the machine and adapted to be moved into position to "knock-off" or release the detent-means whereby to cause actuation of the stopping mechanism of the machine when the package reaches the predetermined size. By this improved construction

of the knock-off device the thread-guide is relieved of undue pressure on the package at the completion of the winding and consequently the machine will operate to produce better packages without danger of crushing the yarn or distorting the shape of the package. It has also been demonstrated that with the present improved sizing device provided with micrometer adjusting means greater accuracy can be secured in sizing the packages and also greater uniformity obtained in the size and weight of a given number of packages containing the same kind of material.

Referring to the present drawings, the machine to which the present invention is shown as applied comprises a box-like frame 2 supporting bearings for a horizontal winding spindle 5 on which the package is wound and having bearings for a cam-shaft 6 arranged therebelow. The cam-shaft 6 is usually driven from the winding spindle 5 by means of a belt and pulleys, or by gearing, and a helical cam 1 is mounted fast on the shaft, see Fig. 3, for reciprocating the thread-guide 10 which traverses the yarn lengthwise of the spindle. Pivoted on the cam-shaft 6 is a traverse-frame 8 for mounting the thread-guide 10 to adapt it to reciprocate longitudinally of the winding spindle 5 and to recede therefrom during the growth of the package being wound on the spindle. The thread-guide 10 is mounted at the end of a traverse-bar or rod 11 which slides in grooves 12 extending longitudinally of the traverse-frame 8, the upper portion of the guide being supported to slide along the face of a plate 13, called the traverse-frame back, which is fastened to the traverse-frame. The traverse-frame back 13 mounts a thread-ball 14, see Figs. 2 and 3, having its legs held in the bores of bosses 15 projecting rearwardly from the back. The strand of yarn y is adapted to feed upwardly from a tension-device, shown generally in Fig. 1 and designated 16, whence it passes through a slub-catcher or yarn-cleaner 17 to lead across the bail 14 and thence through a notch in the thread-guide 10 with its end secured to a suitable package core or cop-tube C mounted on the winding spindle 5. The tension-device 16 and slub-catcher 17 are not herein shown and described in detail as they form no part of the present invention.

The winding spindle 5 may be driven from a prime-mover such as an electric motor and, as before indicated, is belted or otherwise connected to drive the cam-shaft 6. Starting and stopping means are provided for controlling the operation of the machine through a clutch or other suitable mechanism, not shown in the present drawings but which may be of the form and construction illustrated and described in United States Letters Patent No. 2,116,453 to G. N. Taylor, dated May 3, 1938. The starting and stopping mechanism is controlled and actuated through the means of a rockable shaft or rod 20 mounted in suitable bearings on the upper part of the frame 2, one of which is shown at 21 in Fig. 3, and provided at its forward end with a manually-operable lever or handle 22. Fast on the rearward end of the rod 20 is a lever 25 having two arms 26 and 27 formed with wedge-like means at their ends for shifting the clutch-element into or out of engagement with the power-driven means of the machine, this mechanism being disclosed in the prior United States patent referred to above. The lever 25 is adapted to be rocked in clockwise direction by means of the handle 22 to cause the arm 27 of the lever

to engage the clutch with the driving means to rotate the spindle 5 and start the winding operation. A coil-spring 28 fastened to the arm 26 of the lever 25 and anchored at its opposite end to the machine frame 2 is employed for rocking the lever 25 in counterclockwise direction to release the clutch to arrest the rotation of the spindle 5. A brake-shoe 23 on an arm of the lever 22 is adapted to engage with the periphery of a brake-disk 24 on the spindle 5 to promptly check its rotation. The drive is maintained operative by locking the lever 25 in the position shown in Fig. 1 through the engagement of suitable detent-means as next described.

Fast on the forward end of the rock-shaft or rod 20 is a lever 29 formed with an arcuate arm 30 having a detent-lug 31 at its end. The edge of the detent-lug 31 is adapted to engage with a detent-shoulder 32 on a stopping lever 33 to maintain the lever 25 locked in the position illustrated in Fig. 1 and the drive operative. The lever 33 is pivoted on a screw 34 fastened in the machine frame 2 and is formed with an arcuate quadrant 35 which serves for another purpose; that is, as a part of the dogging means which act against the traverse-frame 8 to resist movement of the thread-guide toward the winding spindle.

The dogging means are of usual construction comprising an arm or dog 36 pivoted to the traverse-frame 8 at 37 with its opposite end of tapered formation adapted to slide in a tapered groove 40 in the quadrant 35, shown in Fig. 3. Referring to Figs. 1 and 3 the dog 36 may be released by means of a finger-lever 38 pivoted on the traverse-frame 8 and acted on by a leaf-spring 39 to normally maintain the dog frictionally engaged with the tapered groove 40 in the quadrant 35. Through this arrangement the thread-guide 10 is adapted to move outwardly away from the winding spindle without resistance from the action of the dog 36, but movement of the traverse-frame 8 and thread-guide toward the winding spindle is checked or resisted by the frictional gripping action of the dog 36 on the quadrant 35.

Pivotedly mounted at the outer end of the quadrant 35 is a pendant lever 41 employed for lifting the lever 33 to release the detents 31 and 32 and cause the stopping mechanism to act to arrest the operation of the machine when the yarn breaks or its supply is exhausted. The lever 41 is of triangular form having one arm 42 terminating in a right-angular extension or bail 43 adapted to bear against the yarn strand as it feeds up through the slub-catcher 17; while the opposite arm 44 projects into position for its end to be engaged by the teeth on a wheel or ratchet-disk 45 fastened to the end of the cam-shaft 6 and rotatable therewith in the direction indicated by the arrow in Fig. 1. The lever 41 is so balanced that upon breakage of the yarn or exhaustion of its supply the lever 41 will swing to the left, as viewed in Fig. 1, to engage the end of its arm 44 with one of the teeth on the disk 45 whereby to lift the lever 33 and thereby release the detents which maintain the stopping mechanism inoperative.

The present improved sizing device is also adapted to effect lifting of the lever 33 to release the detents, a positively-reciprocated knock-off element or pitman 50 being employed for this purpose. The pitman 50, shown in detail in Fig. 4, comprises a circular hub 51 from which projects an arm 52 continued in an extension 53

bent or folded at right-angles to the main portion of the arm. The extension 53 of the pitman 50 is formed on one side with a ledge or shoulder 57 and provided at its upper end with a loop 58 enclosing a longitudinal slot 59. The hub 51 of the pitman 50 is rotatably mounted on an eccentric 55 formed as a part of the disk 45, previously referred to as fastened to the end of the cam-shaft 6. As shown in Fig. 3, the disk 45 is fastened to the end of the cam-shaft 6 by means of a stud 46. The disk 45 is bored axially to receive a thimble 47 secured therein by a driving fit and a helical spring 48 held within the bore of the thimble bears against the head of the stud 46 to hold the disk pressing against the end of a bushing 49 in the bearing in which the cam-shaft 6 is mounted; this arrangement being of usual construction but not essential to the present invention. The rearward face of the disk 45 is turned down to form the eccentric hub 55, shown most clearly in Fig. 3, which fits the bore of the hub 51 on the pitman 50.

Referring more particularly to Fig. 2, the upper looped end of the extension 53 of the pitman 50 is connected to the traverse-frame back 13 by means of a stud 62 to adapt it to reciprocate with respect thereto. Ordinarily the thread-bail 14 is fastened in place on the traverse-frame back 13 by screws 18 in the bosses 15, one of the screws being shown at the left in Fig. 3. In adapting the present sizing device for attachment to winding machines already in use the right-hand screw is replaced by the stud 62, previously referred to, which not only serves to secure one leg of the bail 14 in place but also provides a mounting for the upper end of the pitman 50. For this latter purpose the stud 62 is formed with a reduced extension or shank 63 which projects through the slot 59 at the upper end of the pitman 50. Washers 64 and 65 overlie the opposite sides of the pitman 50 with a nut 66 screwed onto the outer end of the shank 63 of the stud 62. Between the head 67 of the bolt 62 and the washer 64 is a helical spring 68 which tends to hold the end of the pitman 50 bearing against the outer washer 65 while permitting sufficient play to allow the pitman 50 to rock slightly as it is reciprocated from the eccentric 55; this form of construction also providing for adjustment of the upper end of the pitman toward or away from the traverse-frame back 13 by turning the nut 66. Preferably, the washer 65 is lined with fiber or similar material, not herein shown, to exert a slight friction against the slotted end of the pitman 50 whereby to prevent too free movement of the latter.

The above-described form of construction and mounting for the pitman 50 adapts it to move bodily with the traverse-frame 8 as the thread-guide 10 recedes from the winding spindle 5 during the winding of a package; the pitman being continuously oscillated or reciprocated by the rotation of the eccentric 55 on the cam-shaft 6. Mounted for adjustment along the quadrant 35 is a sizing gauge 70 in the form of a clamp adapted to be fastened in fixed position by means of a set-screw 71. As shown in Fig. 3, the gauge or clamp 70 is constructed in the form of a bent sheet-metal strip having a right-angular portion overlying the top of the quadrant 35 and a U-shaped loop therebelow hooked into the groove 40 of the quadrant with its end engaging the bottom thereof when the screw 71 is tightened. Referring to Figs. 2 and 3, the forward side of the gauge 70 is milled or cut away to form a sharp

shoulder 73 against which a square, hardened steel block 75 engages. The block 75 is in the form of a rivet having a shank 76 projecting through a hole in the side of the gauge 70 and riveted over at its end as shown in Fig. 3 to secure the block fixedly in place thereon.

The invention having been described as applied to use on a standard type of winding machine, its method of operation in connection therewith is explained as follows: To prepare the machine for operation, a core or cop-tube C is placed on the spindle 5 and the end of the yarn strand y is drawn up from its supply through the tension-device 16 and slab-catcher 17, thence led across the thread-bail 14 and through the notch in the thread-guide 10 with its end suitably fastened to the spindle or cop-tube thereon.

Prior to starting the winding operation the sizing gauge 70 is adjusted on the quadrant 35 by releasing the set-screw 71 whereby to set the hardened block 75 in position to be engaged by the shoulder 57 on the pitman 50 upon completion of the package to a certain size. Usually, this adjustment is made upon winding the first package to the predetermined size and after this preliminary adjustment of the gauge 70 by sliding it along the quadrant 35 a finer and more accurate setting of the device may be made by turning the nut 66 on the stud 62 to move the pitman 50 toward or away from the traverse-frame back 13. In this way a very accurate and precise adjustment of the parts can be accomplished which will remain fixed so that all packages wound on the machine will be of the same size and weight within extremely narrow limits.

To start the winding operation the traverse-frame 8 is moved into position to place the thread-guide 10 against the surface of the cop-tube C as shown in Fig. 1, the dog 36 being released from the quadrant 35 to allow this adjustment of the traverse-frame by pressing on the finger-lever 38. To start the machine operating the handle 22 is rocked in clockwise direction to actuate the lever 25 and engage the clutch with the driving means, and during this operation the detent-lug 31 on the arm 30 is engaged with the shoulder 32 on the lever 33 in the manner illustrated in Fig. 1. This engagement of the detent-means acts to lock the lever 22 and lever 25 against movement under the tension of the spring 28 so that the drive is maintained operative. The winding spindle 5 will therefore be rotated to wind on the yarn y while the cam-shaft 6 driven therefrom will rotate the cam 7 to reciprocate the thread-guide 10. As the thread-guide 10 is reciprocated back and forth along the traverse-frame back 13 it will distribute the yarn in helical coils on the spindle 5 to build up a cross-wound package in the usual manner as well known to those versed in the art. As the yarn builds up on the cop-tube C the thread-guide 10 recedes gradually from the winding spindle 5, this recession being permitted by the swinging of the traverse-frame 8 on its pivot on the cam-shaft 6.

As the winding of each package proceeds and the thread-guide 10 is forced outwardly away from the winding spindle 5, the pitman 50 is carried toward the gauge 70 until eventually its ledge or shoulder 57 is in position to underlie the edge of the block 75. It has been explained that the pitman 50 is oscillated or reciprocated constantly by the rotation of the eccentric 55 on the cam-shaft 6 and consequently as the package reaches the size for which the gauge 70 has been

adjusted the shoulder 51 on the pitman comes into contact with the edge of the block 15 during the upward movement of the pitman to thereby lift the lever 33 and release the detents 31 and 32. Upon release of the detents the spring 28 acts to rock the clutch-lever 25 to disengage the clutch-element from the driving means and thereby arrest the operation of the machine. It will be understood that the sizing device acts in the manner above-described during successive 10 operations of the machine to produce packages of uniform size, and when it is required to wind other types of packages the device may be readily adjusted with great precision and accuracy to secure uniform results whatever the type of 15 winding or size of package required.

It will be observed from the foregoing specification that the present invention provides a novel and ingenious sizing mechanism which is adapted for use on practically all types of winding machines either inbuilt in the mechanism thereof or applied thereto as an attachment. While the invention is herein illustrated and described as embodied in a certain form of construction it is to be understood that modifications may be made in the structure and arrangement of its parts without departing from the spirit or scope of the invention. Therefore, without limiting myself in this respect, I claim:

1. In a winding machine, means for winding a package, stopping means for arresting the winding operation, and a going member continuously actuated from the winding means and so constructed and arranged as to be movable by and with the growth of the package to engage the 35 stopping means and operate the latter when the package reaches a predetermined diameter.

2. In a winding machine, means for winding a package, stopping mechanism therefor, a going member positively actuated from the winding means, and means movable by the growth of the package to continuously shift said going member to cause it to engage the stopping mechanism and actuate the latter when the package reaches a predetermined diameter.

3. In a winding machine, means for winding a package, stopping mechanism therefor, a continuously oscillated member separate from but actuated by the winding means, and means for shifting said oscillating member during the progress of the winding to cause it to engage the stopping mechanism and actuate the latter when the package reaches a predetermined diameter.

4. In a machine for winding yarn into packages, stopping mechanism therefor, a member for actuating the stopping mechanism, said member being separate from the winding means, means for oscillating said member during the winding, and means operated by the growth in the winding for moving said member into position to engage the stopping mechanism and actuate the latter when the package attains a predetermined diameter.

5. In a winding machine, the combination with the winding means, of stopping mechanism therefor, a member movable by and with the growth of the package being wound, means for continuously oscillating said member from the winding means, and means engageable by said member when the package reaches a predetermined size to actuate the stopping mechanism.

6. In a winding machine, means for winding a package, stopping mechanism therefor, a going member, a gauge for regulating the size of the package being wound, means operable by said 75

gauge to initiate operation of the stopping mechanism, and means operative by the growth of the package to shift the going member into position to engage the gauge when the package reaches a predetermined diameter.

7. In a winding machine, means for winding a package, stopping mechanism therefor, a gauge for actuating the stopping mechanism, means for adjusting the gauge to control the size of the package, a going member actuated from the drive of the machine, and means for progressively advancing said going member toward the gauge during the progress of the winding to cause it to engage the gauge to actuate the stopping mechanism when the package reaches a predetermined diameter.

8. In a winding machine, means for winding a package, stopping mechanism therefor, a gauge for actuating the stopping mechanism, a going member actuated from the drive of the machine, means for adjusting the relative position of the going member and gauge prior to the winding operation, and means for progressively advancing the going member toward the gauge in proportion to the progress of the winding to cause it to engage the gauge when the package reaches a predetermined diameter.

9. In a winding machine, means for winding a package, stopping mechanism therefor, a knock-off member separate from the winding means but movable bodily by and with the growth of the package being wound, means for continuously reciprocating said knock-off member, and means engageable by said knock-off member to initiate the operation of the stopping mechanism when the package reaches a predetermined diameter.

10. In a winding machine, means for rotating a package, means for traversing yarn on the package, means to permit separation between the package rotating means and traversing means during the growth of the winding, a going member having a constant cycle of operation and movable in proportion to the separation between the package rotating means and traversing means to continuously change its locus of operation, stopping mechanism for arresting the operation of the machine, and means engageable by said going member at a predetermined locus of its operation to initiate the operation of the stopping mechanism when the package reaches a predetermined diameter.

11. In a winding machine, a winding spindle, means for traversing yarn on the spindle to wind a package, said winding spindle and traversing means being separable during the growth of the winding, stopping mechanism for arresting the operation of the machine, an oscillating member, and means to shift said oscillating member to progressively advance its locus of operation during the separation of the winding spindle and traversing means to cause it to actuate the stopping mechanism when the package reaches a predetermined size.

12. In a winding machine, a winding spindle, a thread-guide for traversing yarn on the spindle to wind a package, a frame for supporting said thread-guide to adapt it to move away from the winding spindle during the growth of the package, a knock-off member reciprocable on said frame, means to reciprocate said knock-off member, stopping mechanism for the machine, and means engageable by said knock-off member to actuate the stopping mechanism when the package reaches a predetermined size.

13. In a winding machine, a winding spindle, a thread-guide for traversing yarn on the spindle, a traverse-frame for supporting the thread-guide to move away from the winding spindle during the growth of the package wound thereon, a pitman reciprocably mounted on said traverse-frame, means for reciprocating said pitman during the operation of the machine, and means engageable by said pitman at a predetermined point in its movement with the traverse-frame away from the winding spindle to actuate the stopping mechanism when the package reaches a predetermined size.

14. In a winding machine, a winding spindle, means for traversing yarn on the spindle, a frame for supporting the traversing means to adapt it to separate from the winding spindle during the growth in the winding, a pitman mounted for reciprocation on said frame, an eccentric for reciprocating said pitman, stopping mechanism for arresting the operation of the machine, and means engageable by said pitman at a predetermined point in its movement with the traverse-frame away from the winding spindle to actuate the stopping mechanism when the package reaches a predetermined size.

15. In a winding machine, a winding spindle, a thread-guide for traversing yarn on the spindle to wind a package, a frame for supporting said thread-guide to adapt it to recede from the winding spindle during the growth of the package, an eccentric, a pitman on the frame reciprocated by said eccentric, a bearing for the pitman adapted for adjusting the latter relatively of the traverse-frame, stopping mechanism for arresting operation of the machine, a gauge engageable by the pitman to actuate the stopping mechanism when the package reaches a predetermined size, and means for adjusting said gauge in position to regulate the size of the package.

16. In a winding machine, a winding spindle, means for traversing yarn on the spindle, a member movable by the growth of the winding, a pitman supported on said member, means for reciprocating said pitman, means engageable by the pitman at a predetermined point in its movement with the member on which it is mounted to

actuate the stopping mechanism, and micrometer means for adjusting the position of the pitman on its supporting member.

17. In a winding machine, means for rotating a package, a pivoted traverse-frame, means carried by said traverse-frame for distributing yarn on the package, a pitman mounted on the traverse-frame, means for reciprocating said pitman, means for supporting one end of the pitman to adapt it for adjustment toward and away from the traverse-frame, stopping mechanism for arresting operation of the machine, and means engageable by the pitman to actuate the stopping mechanism when the frame is moved to a predetermined extent by the growth of the package.

18. In a winding machine, a winding spindle, a thread-guide for traversing yarn on the spindle to wind a package, a traverse-frame for supporting the thread-guide to move away from the winding spindle with the growth of the winding, a pitman slidably mounted on the traverse-frame, an eccentric for reciprocating said pitman, a bearing on the traverse-frame for supporting the end of the pitman, micrometer means for adjusting said bearing to vary the position of the pitman with respect to the traverse-frame, stopping mechanism for arresting the operation of the machine, and means engageable by the pitman to actuate the stopping mechanism when the traverse-frame is moved to an extent to complete a package of predetermined size.

19. In a winding machine, a winding spindle, a cam-shaft, a traverse-frame pivoted on said cam-shaft, a thread-guide mounted for reciprocation on the traverse-frame, a cam on the cam-shaft for reciprocating the thread-guide, a pitman mounted on the traverse-frame, an eccentric on the cam-shaft for reciprocating the pitman, stopping mechanism for arresting the operation of the machine, detent-means for normally maintaining said stopping mechanism inactive, and means engageable by the pitman to release the detent-means to cause actuation of the stopping mechanism when the package reaches a predetermined size.

HAROLD WOOD HITCHCOCK.
